AUTOMATIC SAFETY LIGHTING SYSTEM

John William Lackey, North Creek, N. Y.

Application August 15, 1934, Serial No. 739,990

1 Claim. (Cl. 177—311)

The present invention relates to new and useful improvements in automatic safety lighting systems, the same being an improvement on my co-pending application Serial No. 693,033, now abandoned.

The principal object of the present invention is to provide a simple and expeditious system of lighting automobiles and other vehicles wherein the lamps of the vehicle are equipped with multiple filament bulbs and connected up in such a manner in the system so that in the event one filament of a bulb or its circuit becomes disrupted, the other, or another, will be immediately cut into service.

Another important object of the present invention is to provide a lighting system for vehicles which will serve to put the driver on notice that certain filaments of his multiple-filament bulbs are burned out, or their circuits are disrupted when such is a fact.

Another important object of the present invention is to provide a system of the character stated which will be substantially fool-proof in operation.

These and various other important objects and advantages of the invention will become apparent to the reader of the following specification.

In the drawings:

Figure 1 is a diagrammatic view showing the type of system employing the auxiliary filament in the right headlight bulb.

Figure 2 is a diagrammatic view showing the electrical connection between the electrical devices involved in conjunction with the pilot light.

Figure 3 is a side elevational view of the form of relay employed.

Figure 4 is a front elevational view of the pilot light box.

Referring to the drawings wherein like numerals designate like parts, it will be seen that a description of the simplified form of the invention shown in Fig. 2 will vary but slightly from the system shown in Figure 1, the only distinction being in the accommodation of the auxiliary filament in the right headlight bulb (see Figure 1) which is employed in some makes of vehicles to cause the right headlight to be deflected toward the right or roadside.

In considering Figure 2, it can be seen that the numeral 5 designates the source of current from which the lead 6 extends to the light switch 7. A lead 8 also extends to the stop light switch 9 and from there a jumper 10 extends to the armature 11 of the relay E. A wire 12 extends to the common conductor 13 while another conductor 14 has

the high beam switch 15 interposed between the same and the wire 12. One end of the conductor 14 connects to one end of the coil of the relay A, while the other end of the conductor 14 connects to one end of the coil of the relay C.

The conductor 13 at one end connects to the contact 16 and at its opposite end to the armature 17 of the relay F and also at 18 to one end of the coil of the relay F, the opposite end of the coil of the relay F being connected to the bulb 19 of the usual tail light.

A short jumper 20 is seen in Figure 2, to connect the conductor 13 with the contact 21 which is engageable by the armature 22 of the relay C. This armature 22 is connected to the armature 23 of the relay D besides connecting to one side of the coil of the relay D, while the opposite side of the coil is connected by the conductor 24 to the low beam filament 25 of the right headlight bulb 26. The high beam filament 27 of the bulb 26 is connected by the jumper 28 to the remaining side of the coil of the relay C.

Referring to Figure 2, it will be seen that one side of the coil of the relay E is connected as at 29 to the aforementioned conductor 10 while the other side of the coil is connected as at 30 to the bulb 31 of the stoplight.

From the remaining side of the coil of the relay A, a conductor 32 extends to connect to the high filament 33 of the left headlight bulb 34, while the low filament 35 is connected at 36 to one side of the coil of the relay B. A connection 37 between the armature 38 and 39 of the relays A and B, respectively, is also connected at 40 to the remaining side of the coil of the relay B.

It will be observed at the relay B that the armature 39 operates between a pair of contacts 41 and 42, the contact 41 being connected to the red indicating signal 43 while the contact 42 is connected to the "caution" or amber indicating signal bulb 44.

The armature 23 of the relay D operates between the contacts 45 and 46 which are connected respectively to the red or danger signal 47 and caution signal 48.

The armature 11 of the relay E is in engagement with the contact 49 when attracted by the coil of the relay E, this armature 11 being connected with the conductor 10 from the stop switch 9 while the contact 49 is connected to the green 50 or pilot signal bulb 50.

The red signal bulb 51 is connected to the contact 52 against which the armature 17 of the relay F is engageable when the coil of the relay is de-energized.

It can be now seen that when the light switch 1 is closed, current will flow to the conductor 14 (if the high beam 15 is closed) and will energize both relays A and C, maintaining the armatures 38 and 22 spaced from the contacts 16 and 21, respectively, and at the same time maintaining the high beam filaments 33 and 27 energized.

In the event there is a disruption of the circuit in either bulb, current will flow directly from the conductor 13 and as the armature 38 or 22 has returned to engage the contact 16 or 21 respectively current will flow into the coil of the relay B or D, attracting the armature 39 or 23, respectively to engage the contact 42 or 46, respectively, and at the same time energize the low beam filament 35 or 25 of the right or left headlight bulb, whichever one may be disrupted, leaving the remaining bulb unchanged.

As the contact 42 or 46 is engaged, current is supplied to the caution or amber colored signal 44 or 48, respectively. Thus a caution warning is given to the driver that one or more filaments of his headlight bulbs or the circuits are disrupted.

In the event the stoplight bulb 31 burns out or its circuit is disrupted the coil of the relay E will deenergize and result in the extinguishing of the green pilot lamp 50 indicating to the driver that his stoplight bulb is burned out, or its circuit is disrupted when the stoplight switch is closed by pushing down brake pedal.

In the event the tail light 19 becomes disrupted, the coil of the relay F will de-energize and permit the armature 17 to engage the contact 52 and supply current to the bulb 51 which is red signal indicating the existence of a bad tail light bulb, or the disruption of its circuit. All circuits are adequately fused as shown in Figures 1 and 2.

The form of the invention shown in Figure 1 is quite similar to that shown in Figure 2 with the addition of an auxiliary switch in the high beam switch box 15 or separately located which will be designated as switch 15a, along with an auxiliary filament 26a for the right headlight bulb 26. In conjunction with the auxiliary filament 26a and the switch 15a is the auxiliary relay X which is equipped with the armature 60 operating between the contacts 61 and 62. The contact 61 is connected to the auxiliary caution lamp 63, while the contact 62 is connected to one side of the coil of the relay D and also to its armature 23. It can now be seen that in order to energize the auxiliary filament 26a, the switch 15a must be closed, in which instance current flows from the conductor 13 to the armature 22 of the relay C and from there through the switch 15a and back along the conductor 64 to one side of the coil of the relay X while the other side of the coil is connected directly to the filament 26a which is the auxiliary filament and, as before stated, is used on some automobiles so as to somewhat deflect the light of the right headlight toward the roadside.

When this relay is de-energized, current simply passes from the armature 22 to the armature 60 and from there through the contact 62 to the relay D and through its coil to the low beam filament 25 of the right headlight bulb 26.

Otherwise, the operation of the system in Fig-

ure 1 is identical with the operation of the system shown in Figure 2 and hereinbefore set forth.

Figure 3 shows the type of relay employed which consists of a suitable base 65 having an upright 66 from which extends the contact arm 67 overlying the coil 68 which is upstanding on the base 65. A post 69 is also provided on the base 65 and has an armature 70 rockably supported at the top thereof. A suitable weight 71 can be provided on the outer end of the armature 70 to properly balance armature in center of its weight 70, when spring 72 is not connected and a spring 72 can be employed and interposed between the upright 66 and the outer end of the armature 70 so as to maintain its contact in engagement with the contact 67. It is submitted that the strength of the magnet 68 when energized is approximately two or three to one against the tension of the spring 72 so that the armature 70 can easily be overcome from its engaged position with the contact 67. The relay constructed in accordance with the above details is not susceptible to inefficient operation due to the vibration of the vehicle upon which it is used. An ordinary relay in most cases would be impractical for use in connection with these systems.

It will be observed in Figure 4 that a box 73 is employed for containing the bulbs 43, 44, 47, 30, 48, 50 and 51; this box having slits punched through the front thereof to define arrow shaped windows backed by colored isinglass or a glass of some other character through which light from the bulbs is visible. These windows are 35 designated by character references 44', 43', 47', 48', 50' and 51' correspondingly placed in front of the signal bulbs 43, 44, 47, 48, 50 and 51.

While the foregoing specification sets forth the invention in specific terms, it is to be understood that numerous changes in the shape, size, and materials may be resorted to without departing from the spirit and scope of the invention as claimed hereinafter.

I claim:

In combination with a bulb having a high and a low beam filament, a source of current, a relay including a coil and an armature, a dimmer switch, a connection from the battery to one side of the relay coil and having the dimmer switch therein, a connection between the other side of the coil and the high filament, a back contact adjacent the armature connected to the battery connection on the battery side of the dimmer switch, a second relay including a coil and armature, the first-mentioned armature being connected to the second-mentioned armature and to one side of the second-mentioned coil, a connection between the remaining side of the second-mentioned coil and the low filament, a pair of stationary contacts between which the second-mentioned armature operates, and against one of which contacts said second-mentioned armature normally engages, a "caution" and a "danger" bulb, the "danger" bulb being connected to the last-mentioned contact, while the "caution" bulb is connected to the remaining of the last two mentioned contacts.
